UNITED STATES PATENT OFFICE.

HARRISON B. BOZARD, OF HAMILTON, ONTARIO, CANADA.

FUEL-BURNING APPARATUS.

1,287,852.

Specification of Letters Patent.

Patented Dec. 17, 1918.

Application filed February 14, 1916. Serial No. 78,134.

To all whom it may concern:

Be it known that I, HARRISON B. BOZARD, a citizen of the United States, and resident of Hamilton, Ontario, Canada, have invented 5 a certain new and useful Improvement in Fuel-Burning Apparatus; and do hereby declare that the following is a full, clear, and exact description thereof.

The object of my invention generally 10 stated, is the economical use of fuel in stoves, furnaces, and other heat producing devices, by utilizing to a high degree all the combustible elements of the fuel, and besides important structural improvements, whose ob- 15 jects and advantages are hereinafter fully set forth, I have in view the provision of means whereby air that is preheated may be delivered in the combustion zone or below the grate, and whose course may be auto- 20 matically changed so that its place of delivery will be either the combustion zone or below the grate.

In the accompanying drawings—

Figure 1 is a perspective view of a water 25 heater embodying my invention, a side wall being broken away;

Fig. 2 is a detail view in vertical section through the lower part thereof at the front;

Fig. 3 is a detail view in vertical section 30 on a large scale through the feed passage.

Fig. 4 is a detail view of the adjustable feed door damper.

Referring to the drawings, 10 designates a water boiler adapted for burning coal or coke, having therefor a fuel supporting grate 11 in a base member 12 that contains the ash pit which, as usual, is accessible through a front door 13; 14 designates a feed passage that projects forwardly, its outer end being 15 closed by a hinged door 15. Within the feed passage and forming in effect an elevated false bottom therein, is a shut-off 16 that consists of a plate that extends horizontally from the outer end of the feed passage and 20 its inner end has vertical flange 17 that reaches to the bottom of the feed passage opening at its inner end, so that a chamber closed at its rear end is provided in the lower part of the passage. Within said chamber a short distance in advance of its rear wall, is a vertical partition 18, from the upper edge of which extends horizontally forward a partition plate 19, while from its lower end extends horizontally forward a partition plate 20, the latter being shorter than the upper partition plate above it. The upper parti- 25

tion plate at its forward end terminates in an upwardly and forwardly curved end wall which is perforated by a hole or opening 21 and in advance of and contiguous to said 30 curved wall, is pivoted by means of a rock shaft 22, a radius damper 23 which is adapted to swing between opposite sides of said opening 21 so as to change the direction or 35 flow of current therethrough. The shut-off 40 plate 16 reaches to within a short distance of a plate or diaphragm 24 which is secured by bolts 25 and spacing tubes 26 to the door 15, so as to make the latter a hollow body; the 45 plate 24 not reaching at its lower edge to the 50 bottom of the door, so that thereby communica- 55 tion may be had between the interior of the door and the front end of the chamber below the shut-off 16. Thus, air admitted through the outer wall of the door 15 enters said 60 chamber and if the radius damper 23 is 65 swung to or near a vertical position with its 70 free edge above the top edge of the hole 21, there will be a flow of air horizontally be- 75 tween the shut-off 16 and the horizontal par- 80 tition plate 19, to the rear end of said cham- 85 ber and thence downward through the pas- 90 sage formed by the partition and rear wall of the shut-off plate at the rear end of said chamber and thence forward; whereas, if 95 said radius damper be lowered to a horizon- 100 tal position with its free edge below the bot- 105 tom of the hole 21, the current or draft of air from the hollow door will be reversed and flowing first horizontally rearward, until 110 it reaches the rear end of the chamber and thence upwardly and forwardly, and passing through said hole 21 and above said radius damper 23, will pass through the space be- 115

The forward end of the lower horizontal partition 20 is also curved upward and for-

ward, and contiguous to it is hinged a radius damper 29 which is adapted to swing to and from a port or hole 30 in the bottom wall of the feed passage and from which leads a passage or flue to the ash pit below the grate. Thus, when the radius damper is lifted to uncover said port or hole, the current of air or draft flowing forward from the rear end of the chamber below the feed passage will be prevented from passing beyond said hole by said damper, and accordingly will descend through the hole and find its way into the ash pit below the grate. To cause the two radius dampers to move in unison, I join them by a connecting rod 31, preferably adjustable as by means of a turn buckle 32 at mid-length, the connection between the two dampers being such that, when the damper is lowered to close the hole 30, the damper will be swung to a position with reference to the hole 30, so as to allow the unobstructed draft or flow of air forward through the upper part of the chamber below the shut-off plate 16 and into the feed passage above the shut-off 16. Inasmuch as the radius damper 23 is desired to have a greater swing than the other damper 29, the rod which connects the two dampers has a loose connection with the damper 23 which is supplied by a slot 33 so that even after the damper 29 has come to a rest, continued movement of the damper 23 may take place. The movements of the two dampers are preferably automatically produced, for which purpose I attach to the rock shaft 22 of the damper 23 outside the feed passage a crank arm 34 to which is connected the lower end of a rod or chain 35, whose upper end is connected to the lever of a common form of regulator whose movements are in accordance with the temperature in the furnace, and hence, the draft and the direction of it, whether above the fire or below the grate, are automatically regulated or controlled by the heat requirements of the case. It will be evident that air flowing through the hollow door and through the circuitous passages provided below the feed passage, coming in contact with the heated surfaces of the parts will have its temperature raised before it is delivered into the combustion chamber or below the grate, and to increase the heating effect, within the door, there are alternating inward projections or ribs 36, and in the chamber in the lower part of the pouch, there are similar projections or ribs 37, which act as baffles with which the air comes in contact, and its time of contact with these heated surfaces is prolonged. The size, number and location of the baffle ribs 36 and 37 may be changed as desired, and indeed, in some cases, they need not be employed at all.

When the fire is low, and, hence, there are

few combustible gases being given off from the burning fuel at the top thereof, there is need for the draft or delivery of preheated air beneath the grate so as to promote the combustion of the fuel therein, and it is under these conditions that the damper 29 is moved to a position to fully open the hole 30 while the damper 23 is moved to a position to shut off the draft or flow into the fuel-feeding passage, and to allow air coming through the hollow door to pass through the hole 21, which is controlled by the damper 23. However, until the damper 29 is lowered completely to close the hole 30 for the underdraft, a portion of the preheated air may still pass the damper 23 and find its way to the combustion zone above the fuel in the fire pot, and thus promote the combustion of gases which might otherwise be lost. The loose connection between the two dampers allows such movement of the damper 23 independently of the damper 29 as may be necessary in connection with the conditions just pointed out.

The air is preferably received into the upper part of the door through a damper, or slide controlled passage 38 in the outer wall of the door, and a peep hole 39 having a sheet of mica 39^a is provided through the door to enable the state of combustion within the combustion chamber to be observed, this peep hole being in part formed by the tubular flange 40 that projects from the inner plate 24 to the outer plate of the door. A hinged cover 41 is provided for the peep hole.

To give ready access to the feed passage for cleaning or other purposes, a removable section 42 is provided that includes a portion of the bottom wall of the feed passage at the front, and a portion at each of the opposite sides thereof overlapping parts being provided to receive removable bolt and nut connections 43.

Preferably there is a hole 30, near each side of the feed passage, and from the same a pipe or flue 44 is carried downward and may be connected at its lower end with a nipple 51 on the front wall of the base member 12, which leads into a chamber 46 in the upper part thereof from which numerous ports or openings 47 extend downward and inward into the ash pit, the arrangement of said ports or passages being such that ashes cannot accumulate in them. These ports 47 form a series of openings extending entirely around the ash pit so that the heated air is delivered into the ash pit beneath the grate on all sides. Resting upon the base member 12 is a chambered, ring-form section 48 that extends entirely around the furnace which is added to those furnaces having an inadequate depth of fire pot, and thus deepens the latter, and from the bottom of the chamber 49 in said section passages 50 lead to the

chamber 46, in the upper part of the base member, and in the front wall of said section are nipples 45 for connecting the flues 44. When the connection is between the flues 44 and the section nipples 45, the nipples 51 in the base member 12 are covered or closed, each by a screw cap 52.

It will be evident that the section 48 when placed between the grate carrying base member 12 and the fire pot, not only substantially increases the depth of the fire pot, but since the air coming through the flues 44 for delivery beneath the grate may be passed through the chamber in said section 48, it is still further heated before its final delivery into the ash pit below the grate. Preferably a clean out opening is provided in the front side of the extra section 48 which is ordinarily closed as usual by a suitable door 53.

20 The feed door damper 38 has its throw regulated so that the amount to which it may be moved to open the draft holes may be adjusted and set according to the requirements of the particular case, thus enabling 25 the air supply through the feed door damper in each individual heating apparatus to be no greater than it requires. Said regulating means comprises a thumb screw 53 passing through a threaded opening in a lug 54 on the feed door 15 and a lug 55 on the slide 38 in position to strike the end of the thumb screw 53. When the proper maximum supply of air for the particular heating apparatus is ascertained, the adjustment of the 30 thumb screw 53 is not thereafter disturbed and the damper 38 is simply moved to and fro to open and close the holes, as is usual.

As my invention may be embodied in structures differing from that illustrated in 10 the drawings, it is to be understood that I do not restrict myself to any particular construction unless the language of my claims requires it, and regard myself entitled to such changes as come within the scope of my 5 invention as claimed.

My invention enables the various members to be given a shape or form which especially facilitates or renders easy the casting thereof and the parts are readily assembled 10 and accessible for cleaning and repair, which are important considerations in the matter of original cost and upkeep.

Having thus described my invention, what I claim is—

1. A fuel burning apparatus comprising a fire pot, a grate, a fuel feeding passage leading to the fire pot, having a door at its outer end, an air preheating chamber extending adjacent said fuel-feeding passage from the door inward toward the firepot, having an air inlet, and an air outlet into said passage, whereby air may be passed into the fire pot at said passage, a flue leading downward from said chamber and communicating with the interior of the apparatus below said
2. A fuel burning apparatus comprising a fire pot, a grate, a fuel feeding passage leading to the fire pot, having a door at its outer end, an air preheating chamber extending adjacent said fuel-feeding passage from the door inward toward the firepot, having an air inlet, and an air outlet into said passage, whereby air may be passed into the fire pot at said passage, a flue leading downward from said chamber and communicating with the interior of the apparatus below said
3. A fuel burning apparatus comprising a fire pot, a grate, a fuel-feeding passage leading to the fire pot, having a door at its outer end provided with an air passage, an air preheating chamber adjacent said fuel feeding passage in communication with the air passage in the door, and having an outlet into said fuel feeding passage, a flue leading downward from said chamber and communicating with the space below said grate, and damper mechanism for alternately opening and closing said outlet, and said downwardly leading flue.
4. A fuel burning apparatus comprising a fire pot, a grate, a fuel-feeding passage leading into the fire pot having its outer end closed by a chambered door having inner and outer walls, the chamber within the door being in communication with the external air, and spaced plates in the lower part of the fuel feeding passage one above the other, the space between said plates being in communication with the chamber within the door, the upper plate having its front edge spaced from the inner wall of the door providing a discharge passage for heated air that delivers the air above the uppermost plate into the fuel-feeding passage, a second discharge passage leading from the passage formed by said spaced plates, to the space below the grate, and simultaneously operable dampers for said discharge passages that alternately open and close such openings.
5. A fuel burning apparatus having a fire pot, a grate, an air preheating chamber having outlets that lead, respectively, to the fire pot above the grate and to the space below the grate, and means alternately to close and open communication through said outlets, comprising operatively connected dam-

grate, and means to control the passage of air from said chamber through said air outlet and said flue, that act to shut off the passage of air through one and permit it through the other.

70

2. A fuel burning apparatus comprising a fire pot, a grate, a fuel feeding passage leading to the fire pot, having a door at its outer end, an air preheating chamber extending adjacent said fuel-feeding passage from the door inward toward the firepot, and situated adjacent the bottom of said feed passage, having an air inlet, and an air outlet into said passage adjacent the door, whereby air may be passed into the fire pot at said passage, a flue leading downward from said chamber and communicating with the interior of the apparatus below said grate, and means to control the passage of air from said chamber through said air outlet and said flue, that act to shut off the passage of air through one and permit it through the other.

80

3. A fuel burning apparatus comprising a fire pot, a grate, a fuel-feeding passage leading to the fire pot, having a door at its outer end provided with an air passage, an air preheating chamber adjacent said fuel feeding passage in communication with the air passage in the door, and having an outlet into said fuel feeding passage, a flue leading downward from said chamber and communicating with the space below said grate, and damper mechanism for alternately opening and closing said outlet, and said downwardly leading flue.

90

4. A fuel burning apparatus comprising a fire pot, a grate, a fuel-feeding passage leading into the fire pot having its outer end closed by a chambered door having inner and outer walls, the chamber within the door being in communication with the external air, and spaced plates in the lower part of the fuel feeding passage one above the other, the space between said plates being in communication with the chamber within the door, the upper plate having its front edge spaced from the inner wall of the door providing a discharge passage for heated air that delivers the air above the uppermost plate into the fuel-feeding passage, a second discharge passage leading from the passage formed by said spaced plates, to the space below the grate, and simultaneously operable dampers for said discharge passages that alternately open and close such openings.

pers for the respective outlets, and said air preheating chamber having a removable wall section that forms portions of the bottom and each side thereof.

5 6. A fuel burning apparatus comprising a fire pot, a grate, a base member containing the grate, having a chamber with a series of openings leading therefrom to the space below the grate, and an intermediate member between the fire pot and the base member and above the grate with inner walls flush with the inner walls of the fire pot, and deepening the latter, said intermediate member being chambered and having

its inner walls imperforate, and communicating through its bottom with the chamber in the base member, an air-preheating chamber having outlets that lead, respectively, to the space above the grate, and to the chamber of said intermediate member, and means 20 to discharge air from said preheating chamber alternately to the space above the grate and to the chamber in said intermediate member.

In testimony that I claim the foregoing 25 I have hereunto set my hand.

HARRISON B. BOZARD.
